UNITED STATES PATENT OFFICE.

HUBERT C. HART, OF UNIONVILLE, ASSIGNOR TO THE RUSSELL & ERWIN MANUFACTURING COMPANY, OF NEW BRITAIN, CONNECTICUT.

MANUFACTURE OF KEYS.

SPECIFICATION forming part of Letters Patent No. 248,095, dated October 11, 1881.

Application filed May 9, 1881. (No model.)

To all whom it may concern:

Be it known that I, HUBERT C. HART, of Unionville, in the county of Hartford and State of Connecticut, have invented certain new and 5 useful Improvements in the Manufacture of Solid Keys, of which the following is a specification.

My invention relates to the manufacture of solid keys, preferably of steel, from a bar specially designed for said manufacture by means of cutting-dies and swaging-dies; and the objects of my invention are to produce a merchantable bar from which to manufacture solid keys, and to produce said keys at a small cost.

15 In the accompanying drawings, Figure 1 is a side elevation of said bar. Fig. 2 is a transverse section of the same on line $x x$ of Fig. 1. Fig. 3 is a side elevation of the blank as cut from said bar, and Fig. 4 is a side elevation of 20 a finished key-blank.

I first obtain or make a bar of soft steel of any desired length, in the form shown in Figs. 1 and 2, which bar can be readily made by rolling in the ordinary manner of making bar steel 25 or iron. As seen by the sectional view, Fig. 2, this bar is provided with ribs $a a$ upon opposite sides, and the part b , upon one side of said ribs, is made thick enough for forming the stem of the key, and the part c , at the other 30 side of said ribs, is thinner, so that the shank and bow may be formed therefrom. These ribs are preferably beveled off, as shown, upon that side which faces the thinnest part of the bar.

After said bar is obtained I cut it up into 35 blanks, Fig. 3, by means of a die and punch, which cut on the lines indicated by the contour of said blank. I next strike the blank Fig. 3, when cold, in swaging-dies, which throw or force the stock into the desired form for the 40 finished key-blank, preferably the form shown in Fig. 4, in which figure d designates the ordinary round stem, e the bit-blank, k the stop, f the shank, and g the bow. The bow and bit may be finished and shaped in any ordinary 45 manner.

In striking the blank Fig. 3 to form the blank Fig. 4, the portion which is formed into the stem d is changed from its square form into

the round stem. The bit portion of blank Fig. 3 is flattened and elongated, the square portion 50 at a , Fig. 3, is formed into the rounded stop k , while the shank and bow are compressed and reduced in thickness enough to give them more solidity and a better finish. As in ordinary swaging-dies, some surplus metal, 55 commonly called a "fin," is thrown out from the blank during the swaging process, which surplus metal is taken off by a trimming-die. The finished key-blank Fig. 4 is represented as 60 thus trimmed.

If desired, the blank Fig. 4 may be struck a second time in the swaging-die after it has been trimmed.

All of the above-described operations which are subsequent to the production of the bar 65 are performed when the stock is cold, and thereby the blank is left smooth and bright as it comes from the swaging-dies, so that it can be polished, by tumbling or otherwise, at a small expense. Only a few operations are required, so that a solid steel key is produced at 70 a very small cost.

I am aware that a narrow bar of uniform thickness throughout, except the middle portion, which was provided with rounded beads 75 upon opposite sides, whereby the bar was specially adapted for cutting key-blanks therefrom with the beads running longitudinally with the key-blanks, is old, and is hereby dis- 80 claimed.

I claim as my invention—

The bar Figs. 1 and 2, having ribs $a a$ upon opposite sides, and with the part b upon one side of said ribs of less width and greater thickness than the part c upon the other side of the 85 ribs, the complete width of the bar being equal to the length of the key-blank to be produced, and the bar being specially adapted for cutting key-blanks therefrom, with the ribs of the bar running transversely to the length of the 90 key-blank, substantially as described, and for the purpose specified.

HUBERT C. HART.
